UNITED STATES PATENT OFFICE

JOSEPH W. SCHIEFFER, OF NEW CANAAN, CONNECTICUT

STORE FRONT

Application filed June 22, 1928. Serial No. 287,484.

This invention relates to store fronts, and its general object is to provide a store front of novel form that is capable of being detachably associated with the front of a building so that the store front can be easily and expeditiously installed or removed therefrom, with the result it can be carried from place to place for attachment to the front of any building desired.

10 A further object of the invention is to provide a store front that is formed in a manner so that it will simulate a lunch wagon or like device.

Another object of the invention is to provide a store front that is simple in construction and inexpensive to manufacture and install.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a front elevation of a store front constructed in accordance with the present invention and showing the same applied to the front of a building.

Figure 2 is a sectional view taken approximately on line 2—2 of Figure 1.

35 Figure 3 is a sectional view taken approximately on line 3—3 of Figure 1.

Figure 4 is a top plan view.

Figure 5 is a detail view showing a portion of the store front and illustrating the manner 40 of covering the space between the store front and building and at the ends thereof.

Referring to the drawings in detail, the letter A indicates a building and B the cornice work thereof.

45 The store front which forms the subject matter of the present invention is designed to be detachably associated with the front of a building so that it can be moved from building to building as desired and includes a pair 50 of spaced walls 1 and 2 which are provided

with a curved top 3 so as to simulate the roof of a lunch wagon or other vehicle and secured to the curved top is an elongated strip of material 4 shaped to follow the curvature of the top. The strip 4 is relatively wide and is secured to the curved top 3 so that its major portion extends outwardly in overhanging relation with respect to the walls 1 and 2 as best shown in Figures 1 and 2 of the drawings.

55 The walls 1 and 2 have formed therein a plurality of registering openings 5 and these openings are closed by windows 6 which may be mounted for slidable movement in the usual manner as will be apparent. A door 65 opening 7 is likewise formed in each of the walls 1 and 2 and this opening 7 is closed by a door 8 hingedly secured in any well known manner.

60 Any number of window openings 5 may be provided and in the present construction I have illustrated seven openings in the walls, three of which are disposed upon one side of the door opening, while one is disposed on the other side thereof. Arranged adjacent the top of the walls 1 and 2 is a pair of window openings 9 that are relatively smaller than the openings 5 and these window openings 9 are likewise closed by windows which are preferably secured in fixed position.

65 The store front may be secured in contacting engagement with the front of a building when no projecting parts are included in said building, but when cornice such as indicated by the letter B extends outwardly from a 75 building, the store front must necessarily be secured in spaced relation to the front of the building and in this event I provide spacing blocks 10 which are adapted to receive bolts 11 having nuts, and the bolts are passed 80 through the walls 1 and 2 adjacent the respective corners thereof as best shown in Figure 1 of the drawings.

85 In order to cover the space between the store front and the front of the building, 95 there is provided cover plates 12 for the ends of the front and a similar plate 13 for the top. The plate 13 is curved to follow the curvature of the strip 4 and each of the plates 12 and 13 are provided with slots 15 100

for receiving bolt and nut connections 16 passing through the strip 4 and end strips 17 that extend inwardly from the outer edges of the inner wall 2 as best shown in Figure 3.

5 By this construction, it will be obvious that the cover plates 12 and 13 are adjustably associated with the store front for the purpose of covering spaces of various widths that may occur between the store front and 10 the front of buildings when the store front is moved from building to building as will be apparent.

From the above description and disclosure of the drawings, it will be obvious that I have 15 provided a detachable store front that may be secured to most any building such as a residence or the like for converting the same into a store, and the store front is shaped in a manner to simulate a lunch wagon or the 20 like.

It is thought from the foregoing description that the advantages and novel features of my invention will be readily apparent.

I desire it to be understood that I may 25 make changes in the construction and in the combination and arrangement of the several parts, provided that such changes fall within the scope of the appended claim.

What I claim is:

30 A store front of the character described comprising a pair of spaced walls secured together and being provided with window and door openings, windows and a door for closing said openings, said walls being provided with a curved top, a strip secured to the curved top and disposed in overhanging relation with respect to said walls, means for securing said walls to the front of a building, end strips secured to the walls, plates 35 having slots therein, means carried by the strips and received in said slots for adjustably mounting the plates with respect to the strips and holding the plates in adjusted position for closing space between the store 40 front and the front of the building.

45 In testimony whereof I affix my signature.

JOSEPH W. SCHIEFFER.
